UNITED STATES PATENT OFFICE.

LOFTUS PERKINS, OF GRAY'S INN ROAD, COUNTY OF MIDDLESEX, ENGLAND.

REFRIGERATING AND FREEZING APPARATUS.

SPECIFICATION forming part of Letters Patent No. 399,207, dated March 5, 1889.

Application filed May 26, 1888. Serial No. 275,130. (No model.) Patented in England February 18, 1888, No. 2,471; in India May 4, 1888, No. 121; in France May 15, 1888, No. 190,607; in Belgium May 15, 1888, No. 81,805; in Victoria June 13, 1888, No. 5,892; in New South Wales June 14, 1888, No. 725; in Queensland June 16, 1888, No. 494; in Italy June 30, 1888, No. 23,518, and in Brazil October 20, 1888, No. 628.

To all whom it may concern:

Be it known that I, LOFTUS PERKINS, engineer, a subject of the Queen of Great Britain, residing at 6 Seaford Street, Gray's Inn Road, 5 in the county of Middlesex, England, have invented certain new and useful Improvements in Refrigerating and Freezing Apparatus, (for which I have received Letters Patent in Great Britain, No. 2,471, dated February 18, 1888; in Brazil, No. 628, dated October 20, 1888; in France, No. 190,607, dated May 15, 1888; in Belgium, No. 81,805, dated May 15, 1888; in Italy, No. 23,518, dated June 30, 1888; in India, No. 121, dated May 4, 1888; 10 in New South Wales, No. 725, dated June 14, 1888; in Queensland, No. 494, dated June 16, 1888, and in Victoria, No. 5,892, dated June 13, 1888,) of which the following is a specification.

20 It has before been proposed to construct freezing and refrigerating machines of two vessels capable of supporting considerable pressure and communicating with one another at the top through a tube. Into one vessel has been placed a liquid or substance 25 in which a gas has been absorbed, (say an ammoniacal solution,) and this vessel has been heated and the gas driven off and liquefied under pressure in the second vessel, which is 30 kept cool. Subsequently the heated vessel containing the water from which gas has been driven off has been cooled or allowed to cool, and the pressure being thereby reduced the liquefied gas in the second vessel has then 35 again vaporized and been reabsorbed by the water left in the vessel which was previously heated. The temperature in the second vessel containing the liquefied gas has been thereby reduced. Freezing apparatus of this 40 kind as heretofore constructed has possessed many defects, and has not come into general use. When overheated, and when consequently not only the gas but also the water has been driven out from the vessel which is 45 being heated, it has been liable to disastrous explosions. It has also required to be made with pumps and valves, or if of small dimensions has required to be inverted to allow of any water which may have passed over into

the second or cooling vessel being passed 50 back into the first or heating vessel. The mode of applying heat to the vessel has also been defective, and so, also, have been the precautions taken to avoid the passing off of watery vapor from the vessel that is being 55 heated, and to subsequently insure the ready reabsorption of gas by the liquid remaining in this vessel. I remove all these objections. I make the apparatus of a system of hermetically closed pipes so disposed that any water or liquid which passes from the portion of the apparatus that is at times heated may 60 separate itself from liquefied gas at the cooler end of the apparatus, and pass back by gravity to the part of the apparatus that is being 65 heated, so that no injury can possibly arise to the apparatus from overheating, as any water or liquid distilled over with the gas from the boiler or heated end will, when all ammonia or gas has been driven from that end, flow 70 back again, and so a continuous circulation will be kept up, and the only evil that could arise would be that the apparatus would then be working as a heating apparatus; but the apparatus itself would remain uninjured and 75 ready to act as a cooling apparatus so soon as the heating of the boiler end was stopped and that end allowed to cool. I also, as herein-after described, form the boiler (or that portion of the apparatus which is at times heated) 80 in such a manner as to hinder the passing off of watery vapor from it and to facilitate the reabsorption of ammonia by the water left in it when it is allowed to cool.

In the drawings annexed I have shown apparatus constructed as above described.

Figure 1 is a longitudinal section of the apparatus applied to maintain a low temperature in a room or inclosed chamber. Fig. 2 is 90 a vertical cross-section, and Fig. 3 a plan, of the same. Fig. 4 is an elevation of the heating apparatus. Fig. 5 is a vertical section, on a larger scale, of one section or division of the cooling apparatus. Fig. 6 is an elevation, partly in section, of apparatus for cooling 95 liquid contained in a bath or tank. Fig. 7 is a plan view of the same. Fig. 8 is a vertical cross-section through the tank, and Fig. 9 a

cross-section through a portion of the boiler or heated end of the apparatus. Fig. 10 is a cross-section, and Fig. 11 a longitudinal section, of one of the separators by which any water passing into the cooling-pipes is separated from the liquefied ammonia in these pipes and allowed to flow back to the heated end of the apparatus. Fig. 12 shows a simple form in which the apparatus may be constructed.

In Figs. 1, 2, 3, and 5, A is an inclosed chamber with a door, B. Within the chamber, and just below its roof or ceiling, are closed horizontal liquefied-gas pipes C. From one end of each of these passes a cooling-pipe, D, to one or other of a series of other horizontal liquor-pipes, E, which are at a lower level than the liquefied-gas pipes C. The liquor-pipes E have a number of short vertical pipes, F, descending from them and passing into other horizontal lower liquor-pipes, G, their lower ends being about the middle of the pipes G.

Through the pipes G are passed heating-pipes H of smaller diameter, the ends of which are by other pipes, H' coupled to the two ends of a coil of pipe, H², contained in a stove, I. The pipes H H' and coil H² contain water and form a closed system for conveying heat from the stove to the liquid contained in the pipes G. An expansion-bottle, H⁴, of well-known construction, is connected with the pipes H' between the coil H² and the pipes G. When the apparatus is cold, the expansion-bottle is empty, or nearly so. The water expands when heated, so that if the fire were pushed to the utmost the expansion-bottle would be nearly full; but for the expansion-bottle the expansion would burst the pipes. The expansion-bottle, therefore, serves as a safety device to keep the pipes from bursting when the heat applied is abnormal.

The details of construction of this system of hot-water pipes are not shown, as they are well known, and the closed system of hot-water pipes has been used for applying heat for a variety of purposes. At H³ (see Figs. 3 and 4) are valves by which the passage through the pipes H' to any of the pipes H can be closed, while the passage leading through the pipes H' to the other pipes, H, is opened, so that any one of the pipes may be heated without heating the others; or all the pipes might be heated at once.

The pipes C, which are within the cold chamber, have at one end the pipes D passing into them, as above stated, and at their opposite ends are formed, as shown in Fig. 5, with a short vertical trap-pipe, J, passing upward into them. These pipes are closed at the bottom. At the top they are open and come close to the top of the liquefied-gas pipes C. They have also openings J' formed through their sides just above the bottom of the pipes C. Passing up through the closed bottom of the trap-pipes J are vertical overflow-pipes K of smaller diameter. The upper ends of these pipes, which are open,

terminate about at the level of the center of the pipes C. Their lower ends are by a descending pipe, K', which has a U-bend 70 formed in it, connected to the pipes E.

The apparatus is worked in the following manner: Each liquor-pipe G is filled, or nearly so, with a saturated solution of ammonia containing approximately sufficient liquid ammonia to fill the liquefied-gas pipe C. To facilitate the filling of the liquor-pipe G, this pipe has passing from it at the top a small pipe closed at its end by a screw-cap, G'. All air can be allowed to pass off from the pipe 80 by unscrewing this cap. When a fire has been lighted in the stove I and the coil H² heated, the circulation of heated water set up through the pipes H H' can be directed through any one or other of the pipes H. As 85 each pipe H becomes heated, it heats the ammonia solution in the pipe G, by which it is surrounded. Slight pressure is thereby generated in this pipe, and one-half of the liquid contained in it is forced up into the pipes F 90 and E. Any gas driven off from the liquid in the pipe G then has to pass up through the vertical pipes F into the pipe E and to bubble up through the liquid in these pipes. Any steam or watery vapor passing along with the 95 gas will in this way be condensed, and the gas only will pass on to the liquefied-gas pipe C. As the pressure increases, the ammonia liquefies in the pipe C, it being kept cold by reason of its being in the cold chamber. When all 100 or most of the ammonia has been driven off from the water in the liquor-pipe G, the flow of heated water can be shut off from the heating-pipe H, which passes through it, and the flow directed through another, and so on 105 continuously, each one being in turn heated, and so the fire in the stove I may be kept burning continuously. As each pipe G after being heated gradually cools down, the pressure in this pipe decreases and a vacuum is 110 formed in its upper part, the liquid ammonia in the liquefied-gas pipe C vaporizes by degrees, some of it passes downward through the short connecting-pipes F into the liquid remaining in the lower part of the pipes G 115 and bubbles up through the liquid to fill the vacuum in the upper part of this pipe, and keeps this liquid agitated, so that the liquid readily reabsorbs the gas and the vaporization of the liquid ammonia goes on freely, and 120 consequently the pipe C is cooled down to a low temperature. If it be desired to accelerate the reabsorption of the ammonia by the water left in the pipes G, and thereby accelerate the cooling down of the pipe C, the cooling of this 125 water may be accelerated by allowing cold water to trickle over the exterior of the pipes G, or by causing a stream of cold water to flow through a pipe passed through them, or may be accelerated in other convenient way. If 130 when heating any one or other of the pipes G the application of heat is carried on for too long a time, and the water contained in it is vaporized and condensed in the cold pipe C,

the liquid-level in these pipes will rise above the top of the overflow-pipe K, and liquid will rise up from the bottom of the pipe C through the trap-pipe J and pass away by the descending pipe K', and through the U-bend formed in it to the pipe E, and from thence to the pipe G. Thus if heat be applied for too long a time to any of the pipes G these pipes will constantly have liquid passing back to them from the pipes C, and this liquid will be composed of water having ammonia in solution, ammonia solution being of considerably greater specific gravity than liquid ammonia, so that water accumulating in the pipes C will separate itself from the liquid ammonia and settle to the bottom of these pipes. Consequently, even when the application of heat to the apparatus has been continued for a long time, the apparatus will still remain capable of producing cold in the pipes C whenever the liquor-pipes E and G are allowed to cool. Another advantage is that if the liquor-pipes G are heated directly by fire heat all chance is avoided of the pipes being over-heated and accidents happening in consequence. There will always be liquid passing back to the pipes, and a circulation of heat will thereby be maintained through the liquefied-gas pipes C.

30 A solution of ammonia is not the only solution which may be used in the apparatus. Other solutions which will act in the same way may be used. If the solution is of such a nature that the liquid which is the last to distill over is lighter than the liquid which distills over first, then the pipes J K need not be used; but the pipe K' might be carried up, as shown by dotted lines in Fig. 5, to act simply as an overflow from the upper part of the pipe C.

In order that the ammonia-gas passing to the pipes C may be comparatively cool, the pipe D is, as shown, surrounded by a water-jacket, L, through which a flow of water is maintained.

Chambers or rooms cooled by apparatus formed in the above manner may be utilized for a great variety of purposes. They may, for example, be used for storing meat, or as 50 cool cellars for breweries, or may be used for the manufacture of ice. In this latter case it is convenient to form the chamber or room with an inner chamber kept at a considerably lower temperature than the outer room. In 55 the inner room metallic pails or other vessels containing water may be set to freeze, and when frozen and reduced to a very low temperature may be removed and stored in the outer chamber. I have found that when water is in this way submitted to a low temperature, when absolutely at rest and undisturbed in any way, blocks of perfectly-transparent ice are obtained as clear as glass and free from all air-bubbles.

60 In the apparatus shown at Figs. 6 to 11 two pipes, C, are immersed in brine or uncondensable liquid in a tank, M. Each pipe C is,

as in the apparatus just described, connected by a pipe, D, with other pipes, E F G. Similar provision is also made for heating the 70 pipes. They are shown to be heated by three pipes H passing through them. Provision is also made for allowing watery solution which may accumulate in the pipe C to pass back into the pipe G.

75 The action of the apparatus is the same as above described. The brine cooled in tank M can be made to circulate through vessels required to be cooled or utilized in a variety of ways. In this apparatus, also, I have shown 80 part D^x of the pipe D from one pipe C made to surround part of the pipe D from the other pipe C, so that at this point there may be an interchange of temperature between the cold gas passing from one pipe and the warm gas passing 85 into the other.

I do not restrict myself to the use of ammonia solution. Other gas solution might be used instead of it.

The apparatus may be used for cooling and 90 refrigerating in a great variety of ways. For example, it may, when constructed on a small scale, be employed for cooling ordinary icesafes or refrigerators, the cold pipes C being placed within the upper part of the safe and 95 the remainder on the outside. In this case the heating of the pipes G may very conveniently be effected by gas-burners placed below them, so that to keep the interior of the safe cool it would only be necessary to light 100 these burners for a time once or twice a day; and, if desired, automatic apparatus might be used to shut off the gas immediately that the pipes G were sufficiently heated.

105 Fig. 12 shows a simple form in which the apparatus may be constructed. In this case the apparatus is formed of one tube closed at its ends, set up vertically, and having two bends in it. The end of the pipe descending from the upper bend is the part C to be cooled. 110 It has inserted into it pipes J and K to separate saturated solution from liquid ammonia and to convey any solution in the lower extremity of the pipe back to the lower bend, which is the part of the pipe to which heat is 115 applied.

The lower bend is filled with ammonia solution, and when heat is applied to the bend the ammonia vaporizes and is liquefied in the part C. When the lower bend is allowed to 120 cool, the water remaining in it is drawn up into the end of the pipe which rises from the bend by reason of a vacuum being then formed in this end. The liquid ammonia vaporizes and bubble up through the water and is rapidly absorbed by it. The vaporization of the ammonia, therefore, goes on rapidly, and intense cold is produced at the extremity C of the pipe, where the liquid ammonia is contained. If when applying heat to the lower 125 bend of the pipe the application of heat be continued for too long a time, the water contained in it will be vaporized and condensed 130 in the end C, and will pass back again through

the separator-pipes J and K, as in the forms of apparatus previously described, to the point at which heat is being applied, so that at this time a continuous circulation is kept up and 5 all danger from overheating of the apparatus is avoided. When the solution vaporized in the part G of the apparatus is of such a nature that the more readily vaporizable liquid is of greater specific gravity than the liquid 10 which is last vaporized, then the pipes J and K are unnecessary for conveying back this liquid from the part C to the part G, but can be led back through an overflow-pipe whenever the liquid in the part C rises to too high 15 a level, as previously explained

Having now particularly described and ascertained the nature of my said invention and in what manner the same is to be performed, I declare that what I claim is—

20 1. The combination, substantially as hereinbefore set forth, of the cooling-chamber A, a system of hermetically-closed pipes extending into the chamber and outside thereof, the heaters for the pipe system outside of the 25 chamber A and at a level lower than that of the pipes within the cooling-chamber, the overflow-pipes leading from that part of the pipe system to which heat is applied to the pipes within the cooling-chamber A, and opening 30 therein above their bottoms, whereby the ammonia solution is automatically separated from the liquefied ammonia and carried back to the heating part of the pipe system.

2. The combination, substantially as hereinbefore set forth, of a cooling-chamber, A, a system of hermetically-closed pipes leading into said chamber, and also arranged outside thereof, the heaters for the pipe system outside of the cooling-chamber and below the 40 level of the pipes therein, the overflow-pipes extending from the pipes outside the cooling-chamber to the pipes within said chamber and opening therein above their bottoms, and a trap-pipe, J, surrounding the end of the overflow-pipe, through which the ammonia solution separated from the ammonia is carried.

3. The combination, substantially as hereinbefore set forth, of the horizontal liquor-pipe G, (filled with a solution of ammonia or like solution,) the short connecting-pipe F, rising from about the mid-level of the liquor-pipe G, the upper liquor-pipe, E, into which the pipe F extends, the chamber A, the cooling-pipe D, extending from the liquor-pipe E into 55 the chamber A, the liquefied-gas pipe C within the chamber A, at a higher level than the liquor-pipe G, and the overflow-pipe K, con-

necting the liquefied-gas pipe C to the liquor-pipe G, whereby liquid is conveyed from the liquefied-gas pipe C to the former when the liquefied-gas pipe C becomes nearly filled with liquefied gas.

4. The combination, substantially as hereinbefore set forth, of the horizontal liquor-pipe G, (filled with a solution of ammonia or like solution,) a second horizontal liquor-pipe, E, the short connecting-pipe F, rising from about mid-level of the pipe G into the liquor-pipe E, the liquefied-gas pipe C at a higher level than the liquor-pipe G, the cooling-pipe D, passing from the liquor-pipe E to the liquefied-gas pipe C, a trap-pipe, J, rising up into the liquefied-gas pipe C, and provided with an opening at the top and with an opening, J', near the bottom, and the overflow-pipe K, passing from the interior of the pipe J back to the pipe E.

5. The combination, substantially as hereinbefore set forth, of the horizontal liquor-pipe G, the liquefied-gas pipe C at a higher level than the pipe G, the pipe D, connecting the former with the latter, and an overflow-pipe extending into the liquefied-gas pipe C above the lower level thereof and connecting it with the pipe G, whereby the ammonia solution in the pipe C is separated from the liquid ammonia and automatically carried to the pipe G.

6. The combination, substantially as hereinbefore set forth, of the horizontal liquor-pipes G, (filled with a solution of ammonia or like solution,) the liquor-pipes E, the pipes F, rising from about mid-level of the pipes G and extending into the pipes E, the liquefied-gas pipes C at a higher level than the liquor-pipes G, the cooling-pipes D, connecting the former with the latter, and a water-jacket, L, surrounding each pipe D.

7. The combination, substantially as hereinbefore set forth, of two horizontal liquor-pipes, G, (filled with a solution of ammonia or like solution,) liquor-pipes E, arranged over the liquor-pipes G, the pipes F, connecting the liquor-pipes E and G, the liquefied-gas pipes C, and the cooling-pipes D, connecting the pipes C with the pipes E, said pipes D having part of the length of one pipe passing through part of the length of the other pipe.
